CLAIM

The ornamental design for a sheet pile connector, as shown and described.

DESCRIPTION

FIG. 1 illustrates a front perspective view of my design; and, FIG. 2 illustrates a side view of the design shown in FIG. 1. The sheet pile connector is shown with a symbolic break in its length. The appearance of any portion of the article between the break lines forms no part of the claimed design.

1 Claim, 2 Drawing Sheets# US D895,410 S
